(57) **CLAIM**

The ornamental design for a model vehicle pivoting axle carrier as shown and described.

DESCRIPTION

FIG. 1 is an upper, left, front perspective view of a model vehicle pivoting axle carrier showing our new design; FIG. 2 is a lower, left, rear perspective view thereof; FIG. 3 is an upper, right, rear perspective view thereof; FIG. 4 is a lower, right, rear perspective view thereof; FIG. 5 is a left side elevation view thereof; FIG. 6 is a right side elevation view thereof; FIG. 7 is a front elevation view thereof; FIG. 8 is a rear elevation view thereof; FIG. 9 is an upper plan view thereof; and, FIG. 10 is a lower plan view of the model vehicle pivoting axle carrier.

In the drawings, the broken lines illustrate portions of the model vehicle pivoting axle carrier that form no part of the claimed design.

1 Claim, 5 Drawing Sheets
